UNITED STATES PATENT OFFICE.

GEORGE H. GREIMANN, OF GARNER, IOWA.

DITCH-DIGGING MACHINE.

1,085,035.

Specification of Letters Patent. Patented Jan. 20, 1914.

Application filed May 1, 1913. Serial No. 764,901.

To all whom it may concern:

Be it known that I, GEORGE H. GREIMANN, a citizen of the United States, residing at Garner, in the county of Hancock and State 5 of Iowa, have invented certain new and useful Improvements in Ditch-Digging Machines, of which the following is a specification, reference being had to the accompanying drawings.

10 This invention relates to new and useful improvements in grading machines, and more especially to that class designed for the purpose of digging ditches.

An object of this invention is the provision of a ditching machine which employs a movable scoop, and means coöoperating therewith for removing earth from the scoop and depositing it upon a conveyer from whence it will be deposited at one side of the 20 road.

Another object of this invention is the provision in a ditching machine in combination with a scoop, of a plurality of adjustable knives supported adjacent the scoop 25 and adapted to cut the earth wider than said scoop.

Another object of this invention is the provision of novel means for adjusting the scoop and retaining it in its adjusted positions.

A still further object of this invention is to improve and simplify machines of this character, rendering them comparatively simple and inexpensive to manufacture, reliable and efficient in use, and readily operated.

With the above objects in view the invention consists of certain novel details of construction and combination of parts herein- 40 after fully described and claimed, it being understood that various modifications may be made in the minor details of construction within the scope of the appended claims.

For a full understanding of the invention, 45 reference is to be had to the following description and accompanying drawing, in which—

Figure 1 is a side elevation of a grading machine embodying the improvements of my 50 invention. Fig. 2 is a top plan view thereof with parts omitted. Fig. 3 is a detail view partly in section, of a lever hereinafter specifically described. Fig. 4 is a detail view of a catch employed. Fig. 5 is a front elevation 55 of the shovel, and, Fig. 6 is a vertical transverse sectional view thereof.

Referring now to the drawing in which like characters of reference designate similar parts, the ditching machine is shown to comprise a main frame including opposite side 60 members 10 and 11, the frame being supported by the usual front and rear wheeled axles 12 and 13. The front axle is pivotally connected in the usual manner to the frame and is equipped with the usual steering mechanism 14. A motor 15 is mounted upon the frame and is operatively connected as at 16 to the rear axle for the purpose of driving the axle. A pair of vertical bars 17 are secured to the rear ends of the 70 side members 10 and are braced by inclined braces 18 which connect the upper ends of the bars to said side members.

The shovel frame is disposed to extend rearwardly from the main frame and comprises opposite side bars 19 which are pivotally connected near their front ends to the vertical bars 17 by means of a pivot shaft 20. For rocking this frame in order to raise or lower the shovel, cables 21 are connected 75 to the rear ends of the side bars as at 22 and are trained over respective sheaves 23 carried at the upper ends of the vertical bars 17, and are thence connected to a winding drum 24 that is carried upon a shaft 25 80 secured to the inclined braces 18 substantially midway between the ends of the latter, this winding drum being controlled by the usual hand wheel 26 and ratchet 27. By winding the cables upon the drum the rear 85 end of the frame is rocked upwardly, and by unwinding the cables the rear end of the frame is lowered.

A shaft 28 is journaled in bearings transversely of the shovel frame and has fixed 95 thereon a drive pulley 29 and a pinion 30. A belt 31 is trained over the engine pulley 32 and the drive pulley 29 for the purpose of imparting rotary movement to the shaft 28. The pinion 30 engages with a sprocket chain 100 33 that is provided with a pair of stops 34 and 35. This chain passes through slots formed in a lever 36 which is pivoted on a shaft 37 that is disposed parallel to the before mentioned shaft 28. The stops 34 and 105 35 are arranged to alternately engage with the lever upon opposite sides of the pivot shaft whereby movement of the chain is limited.

A suitable reversing clutch 38 is employed 110 to rotate the shaft 28 in opposite directions thereby reversing the movement of the chain

33. The clutch is connected to the lever 36 by means of rods 39 that engage with the lever above and below the pivot shaft and actuate a walking beam 40 which is operatively connected to the clutch shift lever 41 by means of rods 42, whereby the clutch will be reversed by tilting of the lever 36 through the instrumentality of the stops 34 and 35. The lever is equipped at the upper end with a weight 43 which obviously serves to hold the lever in its desired position until such time as actuated to another position. The lever is provided with anti-friction rollers 44 journaled in the slots of the lever 15 for engagement with the chain 33. A plurality of hangers 45 depend in spaced relation from opposite sides of the shovel frame, and support a conveyer 46, which leads from the center of the shovel frame to one side 20 thereof. The conveyer is operated in any suitable manner such as shown at 47.

A pair of swinging shovel supporting bars 48 are pivoted, as at 49, to the side bars of the shovel frame, and have pivoted to their 25 lower ends a scoop shovel 50. Links 51 are pivoted to the free end of the shovel and are provided with slots 52 which receive pins 53 that project laterally from the bars 48, these links permitting of the shovel rising over obstructions. A bail 54 is pivoted to the free end of the shovel and is connected to the one end of the chain 33, the opposite end of this chain being connected by a cable 55 to a bracket 56 carried by the bars 35 48, the bight of the cable being trained over a sheave 57 carried on a shaft 58 journaled in the extreme rear ends of the side bars of the shovel frame. It will be apparent that upon actuation of the shaft 28 in one direction the shovel will be pulled forwardly by the lower end of the chain 33, and upon actuation of the shaft in the opposite direction the shovel will be pulled rearwardly by the cable 55 attached to the upper end of the 40 45 chain.

Spaced guides 59 are attached to the forward end of the shovel adjacent its upper edge, and slidably support opposite knife blades 60, the cutting edges of which project outwardly beyond the opposite sides of the shovel whereby the earth is cut in advance of the shovel to a greater width than the width of the shovel, and thus allows the shovel to act freely in dipping the soil. The 50 shanks of the blades are pivoted as at 61 to the bars 48 above the pins 53, and as the shovel is drawn rearwardly, the lower ends of these blades will, obviously, contact with the surface of the ground at the outset of 55 the movement, the same being guided along the arms of the bail 54. These arms will, therefore, be prevented from interfering with the walls of the ditch and as the shovel is again moved forwardly, into operative po-

sition, said blades will return to their initial 65 positions against the guides 59.

A scraper 62 of a shape corresponding to the interior of the shovel is slidably fitted in the latter and serves to unload the dirt when the shovel arrives at the conveyer 46. 70 The scraper at its rearmost position forms a closure for the shovel and is normally held stationary at the rear end of the shovel while the shovel is taking up its load. The scraper is connected by bolts 63 to upright bars 64 75 which are pivotally connected at the upper ends to the upper ends of the shovel supporting bars 48 by means of links 65 that are normally held against stops 66 carried by the bars 48 by means of helical springs 80 67. The pins 53 which retain the links 51 on the bars 48 extend inwardly from the latter and are adapted to limit the rearward swinging movement of the bars 64, thus forming stops for the latter. The position 85 of the bars 64 at the time the same contact with the pins 53, is such as to dispose the scraper 62 in its rearmost position in the shovel to form a rear wall or the like therefor.

For operating the scraper a catch 68 is 90 pivoted on bracket arms 69 carried by the upright bars 64 and is connected above its pivot to a rod 70 carried by the shovel supporting bars 48 by means of a short cord 71. There is a rod 72 suspended horizontally below the shovel frame by means of bracket arms 73. As the bars 64 are carried forwardly by the loaded shovel, the catch 8 hooks over the rod 72 such engagement taking place about the time the shovel has 95 arrived at the conveyer and is about to be returned to the ditch. As the shovel moves back the cord 71 tautens after the shovel has moved back sufficiently to enable the scraper which has momentarily been held 100 stationary by the catch, to unload the shovel, and releases the catch 68 from the rod 72 thereby permitting of the scraper being carried back with the shovel into the ditch. The entering dirt forces the scraper back 110 until the links 65 contact with the stops 66 whereby the scraper is held stationary in normal position at the rear end of the shovel.

The shovel supporting bars 48 may be 115 adjusted to suit various conditions of service by means of selectively engaging the pivots 49 in a series of bearings 74 and 75 formed in the shovel frame guide bars and shovel supporting bars respectively as 120 shown.

The operation of the machine is as follows: The machine is propelled by means of the motor 15 to the desired locality, and the shovel 50 is arranged to engage with the ground at the rear of the machine. The shaft 28 is then actuated to cause the shovel to be drawn forward through the earth,

which is cut by the knife blades 60 to a greater width than the width of the shovel, as previously described. The shovel is drawn forwardly until it passes from the 5 earth and over-hangs the conveyer 46. The scraper now forces the load from the shovel on to the conveyer which carries the load to one side of the machine and there discharges it. The shovel is then returned to 10 the ditch and the above operation automatically continued.

From the above description, taken in connection with the accompanying drawings, it will be seen that I have provided a machine 15 for digging ditches or the like which will fulfil all the necessary requirements of such a device.

What is claimed, is:—

1. In a ditching machine, an oscillatable 20 shovel, an oscillatable lever, elements connected to said lever on opposite sides of its pivot and to said shovel and serving to oscillate said lever and to actuate said shovel, a driven shaft, a reverse clutch on said shaft, 25 and means connecting said clutch to said lever for reversing said clutch upon oscillation of said lever by said elements.

2. In a ditching machine, a driving shaft, an oscillatable shovel, an oscillatable lever, 30 a chain driven by said shaft and having connection at its opposite ends with the front and back respectively of said shovel, stops on said chain contactable with said lever for oscillating the same, a clutch on said shaft, 35 and means connecting said clutch with said lever for reversing the direction of movement of said chain upon shifting of said lever by said stops to either limit of its oscillatory movement.

40 3. In a ditching machine, the combination with a supporting frame, of bars pivoted thereto and extending substantially horizontally therefrom, a shovel mounted to oscillate on said bars, knives pivoted to said 45 bars and slidably relative to the shovel, and means for removing the contents of said shovel upon movement of the latter to a predetermined position.

4. In a ditching machine, the combination 50 with a supporting frame, of substantially horizontal bars pivoted to said frame, means for raising and lowering said bars; a shovel mounted for oscillatory movement on

said bars, and knives pivotally connected to said bars and movably mounted upon the 55 advance end of said shovel and disposed to cut the earth outside of and in advance of said shovel.

5. In a ditching machine, the combination 60 of a supporting frame, substantially horizontal bars pivoted to said frame, a shovel pivotally connected to said bars, means for oscillating said bars, a scraper within said shovel, means for securing said scraper for simultaneous movement with said shovel, 65 and means for momentarily holding said scraper stationary during movement in one direction of said shovel whereby said scraper forces the load from said shovel.

6. In a ditching machine, the combination 70 with a supporting frame, of bars pivoted to said frame, a shovel pivoted to said bars, links connecting said shovel to said bars whereby said shovel may rise over obstructions, knives pivoted to said bars and slidably engaging the advance edges of the 75 sides of said shovel, a scraper within said shovel, a second set of bars secured to said scraper, links pivotally connecting together the first and second named bars, and means 80 for oscillating the first named bars.

7. In a ditching machine, the combination 85 with a wheeled supporting frame, a transverse conveyer mounted on said frame, horizontally extending bars pivoted on said frame, a shovel mounted to swing on said bars toward and away from said conveyer, knives pivoted to said bars and slidably engaging said shovel, a chain operatively connected to said shovel, means for actuating 90 the chain to move the shovel toward and away from said conveyer, a scraper within said shovel, bars secured to said scraper, and a tripping mechanism between said horizontally extending bars and said scraper bars 95 for momentarily holding said scraper stationary during oscillatory movement of said shovel in a rearward direction, whereby the load is deposited upon said conveyer.

In testimony whereof I hereunto affix my 100 signature in the presence of two witnesses.

GEORGE H. GREIMANN.
